Primary Examiner — Susan Bennett Hattan*Assistant Examiner* — Omeed Agilee(74) *Attorney, Agent, or Firm* — Michael Best & Friedrich LLP(57) **CLAIM**

The ornamental design for a sampling assembly, as shown and described.

DESCRIPTION

FIG. 1 is a front perspective view of a sampling assembly. FIG. 2 is a front view of the sampling assembly in FIG. 1. FIG. 3 is a rear view of the sampling assembly in FIG. 1. FIG. 4 is a right side view of the sampling assembly in FIG. 1. FIG. 5 is a left side view of the sampling assembly in FIG. 1. FIG. 6 is a top view of the sampling assembly in FIG. 1; and, FIG. 7 is a bottom view of the sampling assembly in FIG. 1. The broken lines in the drawings depict portions of the sampling assembly that form no part of the claimed design.
